MAGNETO IGNITION APPARATUS

Wilhelm Walther, Stuttgart, and Heinrich Bischoff, Stuttgart-Botnang, Germany, assignors to Robert Bosch Aktiengesellschaft, Stuttgart, Germany

Application February 12, 1932, Serial No. 592,646,
and in Germany February 21, 1931

5 Claims. (Cl. 123—149)

The present invention relates to magneto ignition apparatus having a rotary magnet and stationary armature coil, in which the distributor disc is driven from the shaft of the magnet.

5 The object of the invention is to produce a magneto which can be constructed of short length in an axial direction, and the interrupter of which is so arranged that it is protected against carbon dust or ozone from the distributor, according as to whether the magneto is fitted with a slip-ring distributor or a spark-gap distributor.

This object is attained, according to the invention, in that the interrupter is arranged in a compartment which contains the interrupter, the 15 armature and the rotary magnet, which compartment is completely separated from the distributor compartment by a wall, the interrupter being mounted on the shaft of the distributor.

In a known magneto the interrupter is also 20 mounted on the shaft of the distributor, but it is arranged together with the distributor in the same compartment, so that it is exposed to the carbon dust from the distributor.

An example of construction of the invention is 25 illustrated in the accompanying drawing, in which:—

Figure 1 is a sectional elevation of a magneto.

Figure 2 is a front elevation of the interrupter.

30 Figure 3 a view of the adjusting arrangement of the stationary interrupter contact, as seen from above.

Figure 4 a section on the line A—A of Figure 3.

The rotary magnet 1 is mounted in the ball bearing 2 in the bearing cover 3 and in the ball bearing 4 housed in the casing 5. Felt rings 6 are provided on the inner side of the ball bearing and these felt rings rub on the armature shaft 7. The winding 8, with the armature core 9, and the armature shanks 10 are arranged in the usual 40 manner above and close to the rotor. In the front wall 11 of the casing 5 is a hollow shaft 12, and secured in this the rotating distributor piece 13 is mounted. The bearing bore is provided with a bush 14 in which the hollow shaft 12 rotates. 45 The toothed wheel 15 of the distributor is keyed on the hollow shaft 12 by means of the key 16. The toothed wheel of the distributor is in engagement with the toothed wheel 17 mounted on the armature shaft.

50 The distributor piece 13 consists of the disc 18, and the extension 20 of the distributor carrying the distributor pin 19. The distributor pin is connected at one end with the finger 21, and against 55 its other end bears a leaf-spring 22, which is con-

nected to one end of the high tension winding 8 of the armature.

The supporting plate 23 of the interrupter is revolubly mounted by means of an annular collar 24 in a bearing ring 25 of the casing wall 11. On 60 the interrupter plate is secured the stationary contact 26, the rocking lever 27 with the contact 28 and the condenser 29. The interrupter plate has two slots 30 through which pass two screws 31 65 screwed into the bearing ring and serving as stops for the interrupter plate. A spring 34 is riveted to the conducting lead 32 between the condenser 29 and the terminal 33 of the rocking contact 28, which spring on adjusting the interrupter into the retarded ignition end position touches the 70 contact screw 31 and thereby short-circuits the magneto. The interrupter cam 40 is formed from the hollow shaft 12 of the distributor. It is lubricated by a lubricating pad 41, which is 75 pressed against it by a spring 42.

The interrupter is adjusted by means of a plate-shaped lever 35, which is fastened to a shaft 37 connected with the adjusting lever 36, and is provided with a slot 38 in which engages a pin 39 mounted in the interrupter plate. The plate has 80 a longitudinal hole 50 through which the armature shaft 7 can pass.

The adjusting device of the stationary interrupter contact is shown in Figures 2, 3 and 4. A flap 43 is bent from the upper edge of the interrupter plate 23, which flap ends in two flaps 44 and 45. The flap part 44 is again bent upwards at right angles to the flap 43, whilst the flap 45 projects out at right angles to the interrupter plate. This projecting edge 46 of the interrupter 90 plate and the flaps 43 and 44 form a U-shaped channel for the holder 47 of the stationary contact 26, in which the contact holder 47 can slide and be adjusted by the screw 48. The projecting flap 45 serves at the same time as an electrode 95 for a safety spark gap, which is formed by this electrode and the terminal 49 of the coil.

We declare that what we claim is:

1. A magneto ignition apparatus comprising a rotary magnet, a stationary armature, an interrupter, a chamber enclosing said magnet, armature and interrupter, a distributor having an extension thereon, a cam mounted on said extension operating said interrupter, a chamber enclosing said distributor and a wall common to and separating said chambers. 100

2. A magneto ignition apparatus comprising a rotary magnet, a stationary armature, an interrupter, a chamber enclosing said magnet, armature and interrupter, a distributor having an ex- 110

6	tension thereon, a cam mounted on said extension operating said interrupter, a chamber enclosing said distributor, a wall common to and separating said chambers and an adjusting lever for said interrupter having a slot therein embracing the shaft of said magnet and pivotally mounted in said wall below the shaft of said magnet.	4. A magneto ignition apparatus as claimed in claim 1 in which a yoke carrying the stationary contact of the interrupter is guided in a channel formed by flaps bent from a plate forming the base of the interrupter.	80
10	3. A magneto ignition apparatus comprising a rotary magnet, a stationary armature, an interrupter, a chamber enclosing said magnet, armature and interrupter, a spring contact extending from the current lead to the condenser, an earthed contact engaging said spring contact when the interrupter is shifted into the retarded ignition position, a distributor having an extension thereon, a cam mounted on said extension operating said interrupter, a chamber enclosing said distributor and a wall common to and separating said chambers.	5. A magneto ignition apparatus comprising a rotary magnet, a stationary armature, an interrupter, a chamber enclosing said magnet, armature and interrupter, a plate forming a base for said interrupter, a flap bent from said plate forming a safety spark gap with earth, a distributor having an extension operating said interrupter, a chamber enclosing said distributor and a wall common to and separating said chambers.	85
